OFFSET PRINTING PRESS

Howard M. Barber, Pawcatuck, Conn., assignor
to C. B. Cottrell & Sons Company, Westerly,
R. I., a corporation of Delaware

Application June 7, 1934, Serial No. 729,365

36 Claims. (Cl. 101—177)

This invention is directed to that type of offset web printing presses in which the printing unit includes a common impression cylinder and two or more pairs of design and transfer cylinders and their inking mechanisms, and with or without moistening mechanisms, said printing unit operating in unison with a suitable web advancing means, such, for instance, as a folder, delivery, feeder, or two or more combined.

10 This invention consists, generally, in a common drive for the web advancing means and the printing unit and a separate drive for the pairs of design and transfer cylinders, means being provided for permitting the driving or stopping 15 of the web advancing means and impression cylinder independently of the pairs of design and transfer cylinders and for permitting the driving or stopping of the said pairs of design and transfer cylinders independently of the web advancing means and impression cylinder.

20 This invention consists, more particularly, in the provision of one motor for driving the printing unit and web advancing means or for driving the web advancing means and the impression cylinder of the printing unit and a second motor for driving the design and transfer cylinders independently of the impression cylinder and web advancing means, means being provided for bringing one motor into, and the other 25 motor out of, operative connection with the pairs of design and transfer cylinders.

This invention consists, still more particularly, in means for separating the design and transfer cylinders of each pair without operatively disconnecting them, means for separating the transfer and impression cylinders without operatively disconnecting them, and means for operatively disconnecting the transfer and impression cylinders without operatively disconnecting the impression cylinder from the web advancing means.

The object of my invention is to provide an offset printing press of the above character whereby the press crews may work independently upon either the web advancing means and its operatively connected impression cylinder when disconnected from the pairs of design and transfer cylinders, or independently upon the pairs of design and transfer cylinders and their inking and moistening mechanisms. Thus, the web may be threaded and advanced through the press and into the folder, if one is employed, without stopping the pairs of design and transfer cylinders; also the pairs of design and transfer cylinders and the inking and moistening

mechanisms may be independently worked upon for various purposes, as for applying a plate to any one or more of the design cylinders or for preparing and adjusting the inking and moistening mechanisms or for gumming the design cylinders, without affecting the running or stopping of the web advancing means and impression cylinder; thereby permitting the press crews to work on the independently operating parts at the same time and thus materially shorten 10 the period consumed for bringing the press into its full printing condition.

A practical embodiment of my invention is represented in the accompanying drawings which illustrate a two color offset web printing 15 press.

Fig. 1 represents a detail top plan view of the printing press, the several coacting levers being omitted for sake of clarity.

Fig. 2 represents a detail side view of the 20 press showing in diagram the printing unit, the web and the web advancing means.

Fig. 3 represents a detail side view showing the gearing through which the web and the several cylinders are driven.

Figs. 4 and 4^a represent a detail side elevation with the various control levers in their respective positions when the common impression cylinder and the two pairs of design and transfer cylinders are contacting and inter-connecting and the press running at full speed.

Figs. 5 and 5^a represent a similar view showing the various control levers in their respective positions when the impression and transfer cylinders are supported and operatively disconnected; the design and transfer cylinders of each pair being in contact and operatively connected and the inking and moistening mechanisms in contact with their respective design cylinders, to permit coactive movement of the pairs of design and transfer cylinders independently of their impression cylinder and the web advancing means, and vice versa.

Figs. 6 and 6^a represent a similar view showing the various control levers in their respective 45 positions when the inking mechanisms are out of contact with their respective design cylinders, the design cylinders out of contact with their respective transfer cylinders, and the transfer cylinders out of contact and operatively disconnected from their common impression cylinder.

Fig. 7 represents a detail vertical cross section on an enlarged scale, taken in the plane of the line VII—VII of Fig. 1, looking in the direction of the arrows.

Fig. 8 represents an enlarged central section through the magnetic clutch which controls the operative connection and disconnection of the transfer and impression cylinders.

5 Fig. 9 represents a detail side elevation on the same scale as Fig. 7, of the motor side of the press.

Fig. 10 represents a central section on the same scale as Fig. 8, of the magnetic clutch for 10 controlling the operative connection and disconnection between one of the drives and the pairs of design and transfer cylinders.

Fig. 11 represents the wiring diagram of the operating control for the various mechanisms.

15 The two color web printing unit illustrated herein comprises a common impression cylinder and two pairs of design and transfer cylinders operatively connected therewith, the design cylinders being denoted by 1 and 2, the transfer cylinders by 3 and 4 and the common impression cylinder by 5. The shafts of these cylinders are respectively denoted by 6, 7, 8, 9 and 10. The inking mechanism for the design cylinder 1 comprises, generally, the inking fountain 25 11, the fountain roll 12, the fountain roll clutch 13, the ductor roll 14, the distributing rolls 15 and the design cylinder inking rolls 16.

The inking mechanism for the design cylinder 2 comprises, generally, the inking fountain 17, the fountain roll 18, the fountain roll clutch 19, the ductor roll 20, the distributing rolls 21 and the design cylinder inking rolls 22.

30 The moistening mechanism for the design cylinder comprises, generally, the fountain 23, the fountain roll 24, the ductor roll 25 and the design cylinder water applying rolls 26.

35 The moistening mechanism for the design cylinder 2 comprises, generally, the fountain 27, the fountain roll 28, the ductor roll 29 and the design cylinder water applying rolls 30.

40 The web is denoted by 31 and it leads from its supply roll 32 to and around the common impression cylinder 5 and from thence to a delivery which, in the present instance, is shown 45 as a folder 33.

45 The web advancing means includes the folder 33 and also the web supply roll drive which is herein shown as an endless tape carrier 34 engaging the periphery of the web supply roll 32 and passing around pulleys 35 and 36 interconnected by a train of gears 37, 38, 39, 40 and 41.

50 Two motors are provided, one motor 42 being arranged to either drive the web advancing means and the printing unit or the web advancing means and common impression cylinder independently of the remainder of the printing unit; and the other motor 43 being arranged to independently drive the said remainder of the printing unit, i. e., the two pairs of design and transfer cylinders and their inking and moistening mechanisms.

55 The drive from the motor 42 to the web advancing means, i. e., the folder 33 and the web supply roll drive comprises the following elements:

60 A gear 44 fast on the motor shaft 45 drives a gear 46 fast on a cross shaft 47. A bevel gear 48 fast on the cross shaft 47 drives a bevel gear 49 fast on a longitudinally disposed shaft 70 50. A bevel gear 51 fast on the longitudinally disposed shaft 50 drives a bevel gear 52 fast on an upright shaft 53 of the folder 33 from which shaft 53 the folder is driven in the usual manner. Another bevel gear 54 fast on its longitudinally disposed shaft 50 drives a bevel gear

55 fast on a cross shaft 56 which shaft has fast thereon a gear 57 which drives a gear 58 fast on a cross shaft 59, which shaft has in turn a gear 60 which drives a gear 61 on the shaft 62 of the belt pulley 35.

5 The drive from the motor 42 to the shaft 10 of the impression cylinder 5 is as follows:

The cross shaft 47 which is driven from the motor shaft 45 through the gears 44, 46 has fast thereon a gear 63 which drives a gear 64 10 loosely mounted on a cross shaft 65. This loose gear 64 drives a gear 66 fast on the impression cylinder shaft 10.

15 The drive from the auxiliary motor 43 to the shaft 10 of the impression cylinder 5 is as fol- 15 lows:

The shaft 67 of the auxiliary motor 43 drives the cross shaft 65 through a reduction gear unit 68, its shaft 69 and magnetic clutch 70. A gear 71 fast on the cross shaft 65 drives a gear 20 72 loosely mounted on the impression cylinder shaft 10. A magnetic clutch 73 is provided for interlocking and releasing the fast gear 66 of the main motor drive and the loose gear 72 of the auxiliary motor drive, both of which gears, 25 as explained above, are located on the impression cylinder shaft 10.

30 The drive from the impression cylinder shaft 10 to the two pairs of transfer and design cylinders and to the inking and moistening mech- 30 anisms for the two design cylinders, is as fol- lows:

The loose gear 72 on the impression cylinder shaft 10 drives two gears 74, 75 fast on their respective transfer cylinder shafts 8 and 9. 35 Gears 76, 77 also fast on their respective transfer cylinder shafts 8 and 9 drive gears 78, 79 fast on their respective design cylinder shafts 6 and 7. These gears 78 and 79 also drive the gears 80, 81 and their respective inking rollers 40 and the gears 82, 83 of their respective moistening mechanisms. Gears 84, 85 fast on the design cylinder shafts 6 and 7 respectively, drive gears 86, 87 which in turn respectively drive gears 88, 89 fast on the shafts 90, 91 of 45 the ink fountain feed mechanisms.

50 Cams 92, 93 fast on the shafts 90, 91 act upon spring pressed rollers 94, 95 carried by arms 96, 97 fast on rock shafts 98, 99. Manually adjustable connections 100, 101 on arms 50 102, 103 fast on the rock shafts 98, 99 are provided for the lower end of connecting bars 104, 105, the upper ends of which bars are connected to arms 106, 107 of rock shafts 108, 109 of the fountain roll clutches 13, 19, to cause the fountain rolls to rotate step by step. Hand screws 110, 111 are journaled in the arms 102, 103 and adjust the connections 100, 101 of the bars 104, 105, to control the movements of the fountain rolls 12, 18.

55 The design cylinders 1 and 2 may be adjusted to bring them into proper printing contact with their transfer cylinders 3 and 4 as, for instance, by mounting the design cylinders on eccentric bearings 112, 113, adjustable rotatively by providing the bearings with arms 114, 115 from which rods 116, 117 extend to studs 118, 119 fixed to the press frame where the rods may be screw-threaded and provided with adjusting nuts 120, 121 cooperating with the studs 70 to move the rods longitudinally.

60 The transfer cylinders 3 and 4 may be adjusted to bring them out of printing contact with their impression cylinder 5 for thickness of stock to be printed, without disturbing their 75

printing contact with the design cylinders 1 and 2; and the transfer cylinders 3 and 4 may also be adjusted to bring them out of printing contact with their design cylinders 1 and 2, when so desired. To accomplish these results the transfer cylinders are mounted on outer and inner eccentric bearings 122, 123 and 124, 125.

The means for adjusting the transfer cylinders 3 and 4 to bring them out of printing contact with their common impression cylinder 5 and into contact with their design cylinders 1 and 2 are as follows:

Hand levers 126, 127 are carried by rock shafts 128, 129, which rock shafts are provided with eccentrics 130, 131 embraced by the upper members 132, 133 of connecting rods, the lower members 134, 135 of which are connected to arms 136, 137 projecting from the outer eccentric bearing 122, 123. Adjusting screws 138, 139 are provided between the upper and lower members 132, 133 and 134, 135 of the connecting rods to regulate the printing contact between the transfer cylinders and their impression cylinder when in printing position.

The transfer cylinders 3 and 4 are adjusted to bring them out of contact with their design cylinders 1 and 2 as well as their common impression cylinder 5, by providing the inner eccentric bearings 124, 125 with arms 140, 141, connected to the upper ends of rods 142, 143, the lower ends of which rods are connected to arms 144, 145, fast on rock shafts 146, 147, which shafts are rocked from a cam 165 on the rotary shaft 148*, through the following connections:

A spring pressed stud or roller 149 is carried by an arm 150 of a lever pivoted at 151, a second arm 152 of which lever being yieldingly connected through rods 153, 154 with forked bars 155, 156 connected at their lower ends to arms 157, 158 of rock levers pivoted at 159, 160, the other arms 161, 162 of which levers are spring pressed and carry studs or rollers 163, 164 which engage the periphery of a cam 165 on the shaft 148*. The operating bars 155, 156 have shoulders 166, 167 and 168, 169 adapted to respectively engage the pins 170, 171 and 172, 173 carried by rock levers 174, 175 fast on the rock shafts 146, 147. The rod 154 is connected to the forked bar 156 through a rock lever 154* and connecting bar 156*.

Means are provided for preventing the hand levers 126, 127 from being rocked except under certain conditions to be hereinafter explained, which means is herein shown as comprising lock bars 176, 177 carried by the inner eccentric bearings 124, 125 in position to engage the diametrically opposed shoulders 178, 179 and 180, 181 carried by the said hand levers 126, 127.

The rock levers 174, 175 have spring pressed connections at the pins 182, 183 with the lower ends of hook bars 184, 185 having at their upper ends recesses 186, 187 and 188, 189 respectively, arranged to engage pins 190, 191 on the operating forked bars 192, 193 which are connected at their corresponding ends to the depending arms 194, 195 of rock levers pivoted at 196, 197, the uprising arms 198, 199 of which levers carry spring pressed rollers 200, 201 which ride on the faces of cams 202, 203, fast on the shafts 6 and 7 of the design cylinders 1 and 2.

The operating bars 192, 193 have two shoulders 204, 205 and 206, 207 respectively, arranged to alternately engage the pins 208, 209 and 210, 211 of rock levers 212, 213 fast on rock shafts

214, 215, which shafts are also provided with depending arms 216, 217 which are connected by rods 218, 219 to the depending arms 220, 221 of rock shafts 222, 223. These rock shafts 222, 223 have eccentrics 224, 25 forming supports for the end plates 226, 227 of the design cylinder inking roll carriages.

These end plates 226, 227 carry pins 228, 229 for engagement with the lower ends of latch bars 230, 231, the upper ends of which latch bars have spring pressed lost motion connections with arms 232, 233 fast to rock shafts 234, 235. These rock shafts 234, 235 have fast thereon latch bars 236, 237, arranged to be brought into and out of engagement with the rock arms 102, 103 carried by the rock shafts 98, 99, the motion of which is controlled by the cams 92, 93 on the shafts 90, 91.

OVERTHROW hand levers are pivoted at 238, 239, the handles being denoted by 240, 241. These hand levers are provided with arms 242, 243 having studs or rollers 244, 245, arranged to be brought into and out of contact with the operating forked bars 155, 156. These hand levers are also provided with arms 246, 247, 25 carrying safety rods 248, 249, arranged to be brought into and out of position to be engaged by lugs 250, 251 on the outer eccentrics 122, 123.

The cams 148 and 165 which are fast on the shaft 148* are driven from the impression cylinder shaft 10 at a selected speed that will not limit the speed of the printing cylinders, through the train of gears 253, 254, 255, 256.

The electrical control for the press comprises the following elements:

The control station 257 for the main motor 42 includes the two "print" switches 258, 259, the "run" switch 260, the "jog" switch 261 and the "stop" switch 262.

The control station 263 for the auxiliary motor 43 includes the "run" switch 264, the "jog" switch 265, the "stop" switch 266, and the "reverse" switch 267.

The main motor clutch magnet is denoted by 268 and its stop switch operated mechanically from the main motor clutch is denoted by 269, its switch which stops the auxiliary motor, by 270, and the maintaining switch for the trip magnet 273, by 271. The auxiliary motor clutch magnet is denoted by 272. The hand operated trip magnet is denoted by 273, the switch by 274 and the plunger by 275. The main clutch magnetic relay is denoted by 276 and its contacts by 277, 278. The main motor slow speed relay is denoted by 279, its main motor slow speed contacts by 280, its contacts for maintaining the main motor by 281, and its contacts for the control circuit for the main motor high speed relay 283, by 282. The contacts for this high speed relay 283 are denoted by 284. The hand operated switch to run the web at high or low speed when the impression cylinder is operatively disconnected from the pairs of design and transfer cylinders is denoted by 285. The auxiliary motor relay denoted by 286 is provided with the contacts 287, 288, 289, 290, 291.

The slow down switches 293, 294 are operated from the inner eccentric bearings 124, 125. The main motor magnetic clutch operating switches 292, 295 are also operated from the inner eccentric bearings 124, 125.

The switch 296 is used for bridging slow down current when the press is printing a single color. The plunger 275 is connected to the hook 75

arm 297 of a rock lever pivoted at 298. This hook lever arm 297 is arranged to be brought into and out of engagement with the uprising arm 152 of the lever pivoted at 151. The other arm 299 of this hook lever pivoted at 298 is arranged in position to be engaged by a swinging latch lever 300 pivoted at 301, which latch lever is connected by a spring pressed rod 302 to the depending arm 303 of a three armed lever pivoted at 304. Another arm 305 of this rock lever is connected through a rod 306 to an arm 307 of a rock lever pivoted at 308, the other arm 309 of which rock lever operates from the main motor clutch 73. The contactor relay is denoted by 310 and its contacts by 311, 312, 313.

In operation

The printing plates and packings may be attached to design cylinders 1, 2, in the usual manner, the switches of the auxiliary motor control station 263 being used to "jog" or "reverse" the design cylinders to permit the ready attachment of the plates to the cylinders.

New blankets may be attached to the transfer cylinders 3, 4, or the cylinders may be cleaned and their old blankets prepared, the switches of the said auxiliary motor control station 263 being also used for this purpose.

The colors are placed in the ink fountains 11, 17 and the ink is fed to the distributing rollers 15, 21, to obtain the proper distribution for printing. To do this the pairs of design and transfer cylinders 1, 3 and 2, 4, the inking mechanisms, and the moistening mechanisms are all operated in unison. The ink is fed by releasing the latch bars 236, 237 from the lever arms 102, 103, to permit the spring pressed rollers 94, 95, carried by the lever arms 96, 97 to be swung upwardly into contact with the rotary cams 92, 93, carried by the shafts 90, 91. Thus, the rotary cams 92, 93 impart a reciprocating motion to the connecting bars 104, 105, thereby causing an intermittent forward movement to the roller clutches 13, 19 which rotate the fountain rolls 12, 18, step by step. The amount of this movement can be adjusted by turning the hand screws 110, 111.

The moistening mechanisms may be prepared by placing water and acid solution in the fountains 23, 27 and transferring the moisture therefrom to the design cylinders 1 and 2 through the rolls 24, 25, 26 and 28, 29, 30, by running the pairs of design and transfer cylinders of the printing unit.

If necessary, the gum may be removed from the printing plates on the design cylinders 1, 2, the "jogging" switch 265 of the auxiliary motor control station 263 being used for this purpose.

The "run" switch 264 of the auxiliary motor control station 263 may then be closed to allow the pairs of design and transfer cylinders to be run together with the inking and moistening mechanisms, it being understood that the rollers 26, 30 of the moistening mechanisms are properly adjusted for the desired amount of moisture to be applied to the design cylinders 1, 2. The inking rollers 16, 22 which have been in their raised position, out of contact with the design cylinders 1, 2, may then be dropped into contact with the surfaces of the design cylinders by unlatching the hook bars 184, 185 from their pins 190, 191, thus allowing the operating forked bars 192, 193 to drop, bringing their shoulders

205, 207 into engagement with the pins 209, 211 on the rock levers 212, 213.

The operating bars 192, 193 which are connected to the arms 194, 195 of the rock levers pivoted at 196, 197 are oscillated by the contact of the spring pressed rollers 200, 201 on the lever arms 198, 199 with the faces of the rotary cams 202, 203 on the design cylinder shafts 6, 7.

The rock levers 212, 213 which are fixed to the rock shafts 214, 215 because of their connection between the depending arms 216, 217, rods 218, 219 and depending arms 220, 221 swing the eccentrics 224, 225 on the rock shafts 222, 223, to permit the end plates 226, 227 of the inking roller carriages to drop, thus permitting the inking rollers 16, 22 to be brought into contact with the peripheries of their design cylinders 1, 2.

The pressman may now examine the plates on the design cylinders 1, 2, to see if the ink and water are functioning properly. He then raises the inking roller carriages, thereby lifting the inking rollers 16, 22 out of contact with the peripheries of the design cylinders 1, 2. This is accomplished by reengaging the hook bars 184, 185 with their pins 190, 191 on the operating forked bars 192, 193, thereby raising the operating bars into engagement with their pins 208, 210 and thus reversing the movement of the rock shafts 214, 215.

During this period of preparing the plates on the design cylinders 1, 2, the pairs of design and transfer cylinders have been constantly rotated at a slow speed except when the pressman has wished to examine the plates closely by operating the stop switch 266 of the auxiliary motor control station 263. It is understood that the pressman may also then operate the "jog" switch 265 of the said station, to bring any particular portions of the plates into ready position for examination.

If satisfied with the condition of the plates on the design cylinders 1, 2, the pressman may then close the "run" switch 264 of the auxiliary motor control station 263 and allow the pairs of design and transfer cylinders to run together with the moistening mechanisms, thus continuously keeping the plates on the design cylinders moist.

Should the pressman desire to stop the pairs of design and transfer cylinders for a considerable period of time he will, of course, gum the plates on the design cylinders, using the "jog" switch 265 of the auxiliary motor control station 263 to permit the application of the gum solution over the entire surfaces of the plates.

If the pressman finds the plates in condition for printing he will then prepare to print on the blankets of the transfer cylinders 3, 4, so that the blankets will be in condition to print on the web passing around the common impression cylinder 5, with a minimum amount of waste. Its printing operation is accomplished by throwing the hand levers 126, 127 from their positions "A" to their positions "B" (see Figs. 5 and 5^a). The latch lever 300 holds the lever arm 299, thus releasing the arm 297 from the uprising lever arm 152 so that pressure between the transfer cylinders 3, 4 and their common impression cylinder 5 cannot be thrown on when the main motor magnetic clutch 73 is out of engagement, unless the hand levers 126, 127 are in their position "B". Otherwise, if pressure were thrown on the transfer cylinders 3, 4, while rotating, they might come

into contact with the impression cylinder when stationary, thus causing damage to web and press.

The levers pivoted at 304 and 308 and their connections 302 and 305, operated by the main motor clutch 73, when thrown out of engagement, places the latch lever 300 in engagement with the arm 299 of the rock lever pivoted at 298.

10 In moving the handles 240, 241 of the overthrow levers pivoted at 238, 239 counter-clockwise, the connecting rods 153 and 154 are moved, thereby pushing the lever 154* and its connecting rod 156* to bring the forked bars 155, 156 into engagement with their pins 170, 173. It will be remembered that these forked bars 155, 156 are moved by their levers pivoted at 159, 160 respectively, through the cam 165 and studs or rollers 163, 164, thus causing the forked bars 155, 156 to push against their respective pins 170, 173, carried by the rock levers 174, 175, thereby moving the outer eccentrics 122, 123 of the transfer cylinders through the connections 142, 143. This operation will throw pressure on between the cylinders.

15 It will be remembered that the cams 148 and 165, mounted on the shaft 148* are timed in relation to each other. This shaft 148* is driven at its lower speed to reduce the strains 20 on the pressure operating mechanism consistent with other normal operating conditions and still not limit the printing or cylinder speed of the press.

25 The handles 240, 241 of the overthrow levers 30 pivoted at 238, 239 may then be thrown. This will hold the forked bars 155, 156 against their pins 170, 173 and the pressure mechanism consisting of the cam 165, cam levers pivoted at 159, 160, their rollers 163, 164, forked bars 155, 156, rock levers 174, 175 and connections 142, 143 will move the transfer cylinder outer eccentrics 122, 123 to pressure position. By returning the handles 240, 241 to their original position the cylinders will be separated to "pressure-off" position.

30 It is only possible to return the hand levers 126, 127 to their positions "A" after pressure has been released, placing both the safety rods 248, 249 and lock bars 176, 177 in non-interfering positions. The safety rods 248, 249 are for

35 the purpose of preventing the operator from operating the pressure mechanism before the hand levers 126, 127 are in correct position. The lock bars 176, 177 will prevent the hand levers 40 126, 127 from being moved to position "A" before pressure between the design and transfer cylinders has been released.

45 It will be observed that either one of the pairs of design and transfer cylinders can be held in non-printing position indefinitely, without interfering with make-ready or printing operation of the rest of the press. This is accomplished by inserting either a stop 314 to prevent the roller 163 from following the cam 165, or a stop 315 to prevent the roller 164 from following the said cam 165.

50 While I have referred specifically to the operating mechanisms for both pairs of design and transfer cylinders and their combined coaction and non-coaction with the common impression cylinder, still it is to be understood that either pair of cylinders may be made ready or remain inactive as far as the printing is concerned if it is desired to run a single color only,

without affecting the speed or efficient operation of the press.

5 From the above description it will be seen that the pressure between the design and transfer cylinders of both pairs may be obtained and the inking mechanism may be raised or lowered, or held out of contact regardless of the operation of the automatic trip mechanism.

It will also be observed that the ink fountain feed for each pair of design and transfer cylinders may be stopped, started, adjusted, or held stopped regardless of the operation of the automatic trip mechanism.

10 Assuming that everything is now ready to start the printing operation:

15 The design and transfer cylinders are running slowly, the ink rollers are raised, the ink fountain feed is stopped, but there is no pressure between any of the cylinders, and the water rollers are in contact with the design 20 cylinders to prevent oxidation.

25 While the design and transfer cylinders are being prepared for printing, the paper web roll may be placed in position and the web threaded through the press. The folder may also be 25 tested and the necessary adjustments made to the operation of the press which consists of the web roll drive, the impression cylinder, and the folder, without interference with the pairs 30 of design and transfer cylinders.

30 It will be observed that this part of the press is driven independently by the main motor 42 and controlled by station 257 when desiring to do any of the operation mentioned in the last 35 paragraph. The "run" switch 260, the "jog" switch 261, the "stop" switch 262 in connection with the hand operated switch 285 and contactor relay 310, are used during this period. While printing, these units are electrically inactive.

40 The circuit through the contacts 311 operates the main motor; the circuit through the contacts 312 are for maintaining circuit for the contactor relay 310; the circuit through the contacts 313 are for energizing the high speed 45 relay 283, to operate the impression cylinder, the folder, and the web control mechanism at high speed when the switch 285 is closed.

To start printing the web

50 It will be kept in mind that the auxiliary motor 43 is driving a portion of the press. Change the "run" switch 260 of main motor control station 257 to the "print" switch 258, thus closing the contacts 259. The current then 55 flows through 258, energizing the relay 279, thus causing the contacts 280, 281, 282 to complete their circuits. The circuit through contacts 280 will start the main motor 42 to run slow speed; the circuit through contacts 281 60 maintains the relay circuit; the circuit through contacts 282 is closed but inoperative until the switch 294 closes by movement of the inner eccentric 124 or 125. The closing of the switch 294 energizes the relay 276 which is of the time 65 element type, thus causing a delay in closing and completing the circuits through the contacts 277 and 278. The circuit through the contact 277 energizes the main clutch magnet 268, thus moving the pins of the magnetic 70 clutch 73 into positive engagement with the fast gear 66 of the main motor drive. This clutch 73 has about a one-fourth inch movement and in closing breaks the switches 270, 271 and closes the switch 269. The circuit through 75

75

the contact 278 of the relay 276 maintains the relay when the switch 292 or 295 is closed by movement of the eccentric 124 or 125. The switch 296 is provided to bridge the slow down circuit if operating one only of the pairs of design and transfer cylinders. The switch 269 is provided for automatically stopping the main motor when printing ceases. Opening the switch 270 breaks the maintaining circuit 10 through the contacts 281 of relay 286, thus stopping the auxiliary motor 43 and deenergizing the clutch magnet 272. Opening the switch 271 breaks switch 274 of the circuit feeding trip magnet 273, causing transfer cylinders 15 to move into contact with design and impression cylinders, as hereinbefore set forth.

It will be noted that the switches 269, 270, 20 271 are mechanically operated by the magnetic clutch 73. Opening the switch 271 ensures the main clutch being in positive engagement before pressure can be thrown on between the cylinders. This is important as all of the cylinders must be driven from the main source to ensure correct peripheral speeds. The movement 25 of the inner eccentrics 124, 125 when pressure is thrown on will close the switches 294, 292, 293 and 295, and will open the switch 296. The closing of the switches completes the circuit through the contacts 282, thus energizing the relay 283 and closing its contacts 284, thus causing the main motor to speed up to its fast printing speed. The press may now be considered as printing correctly at high speed and the operator may remove his finger from the print 30 switch 258 of the main motor control station 35 257.

Four switches 316, 317, 318, 319 are provided 40 for stopping the printing operation according to requirements. The closing of any one of these switches would operate as follows:

If the web should break the switch 316 would close, thus energizing the trip magnet 273 and causing the trip mechanism to operate. This will open the switches 294, 293 and 292, 295. 45 Opening of the switches 294 and 293 causes the current through the contacts 284 to break, thus slowing down the main motor. Opening the switches 292 and 295 causes the current to be broken through magnetic relay 276, thus stopping the current from flowing into the magnetic clutch 73. This clutch 73 moves out of driving 50 contact, thus operating the switches 269, 270, 271. The switch 269 breaks the maintaining circuit through the contacts 281, thus causing the relay 279 to release the contacts and stop the main motor. All of the above operations are automatic and are operated in proper sequence. It is now necessary to close the "run" 55 switch 264 of the auxiliary motor control station 263, to allow the auxiliary motor 43 to run, if it be desired to keep the printing plates moist. If not, it is necessary to gum the plates.

From the above description it will be seen 60 that it is impossible to operate the auxiliary motor or clutch while the press is being driven by the main motor and the web is being printed. It will also be seen that means have been provided whereby the web advancing means and the impression cylinder of the printing unit 65 can be stopped, started, and run entirely independently of the pairs of design and transfer cylinders and the inking and moistening mechanisms for the design cylinders.

It will also be seen that I have provided means 70 whereby the pairs of design and transfer cyl-

inders and the design cylinder inking and moistening mechanisms can be stopped, started, and run independently of the operation of the web advancing mechanism and impression cylinder. It will also be seen that I have provided means whereby each pair of the design and transfer cylinders and the design cylinder inking and moistening mechanisms can be stopped, started, and run independently of the operation of the web advancing means and the common impression cylinder. 10

The above provisions enable, in a multi-color press, the independent handling of the parts as above enumerated, to cause the press to be brought into its full printing condition in the 15 shortest time and with the least wastage of web material.

While I have illustrated a folder as a part of the web advancing means, it is to be understood that I do not wish to limit myself to this particular mechanism but wish to cover any mechanism which it may be desired to use instead of the folder. The parts of the printing press which are shown and described but not claimed herein, form the subject matter of my copending application, filed May 17, 1933, Serial No. 671,451, which has now matured into Letters Patent No. 1,972,470, dated September 4, 1934.

It is also evident that various changes may be resorted to in the construction, form and arrangement of the several parts without departing from the spirit and scope of my invention, and hence I do not intend to be limited to the particular embodiment herein shown and described, but

What I claim is:

1. In a multi color offset printing press, a printing unit comprising a common impression cylinder and pairs of design and transfer cylinders interconnected therewith, their drive, 40 means for separating and means for operatively disconnecting the transfer cylinders from the impression cylinder, and means for driving the design and transfer cylinders independently of the impression cylinder and independently of each other.

2. In a multi color offset printing press, a printing unit comprising a common impression cylinder and pairs of design and transfer cylinders interconnected therewith, their drive, 50 means for separating and means for operatively disconnecting the transfer cylinders from the impression cylinder, and means for driving the impression cylinder independently of the design and transfer cylinders and the design and transfer cylinders independently of each other.

3. In a multi color offset printing press, a printing unit comprising a common impression cylinder and pairs of design and transfer cylinders interconnected therewith, their drive, 60 means for separating and means for operatively disconnecting the transfer cylinders from the impression cylinder, means for driving the design and transfer cylinders independently of the impression cylinder and independently of each other and means for driving the impression cylinder independently of the design and transfer cylinders.

4. In a multi color offset printing press, a printing unit comprising a common impression 70 cylinder and pairs of design and transfer cylinders interconnected therewith, web advancing means, their drive, means for separating and means for operatively disconnecting the design and transfer cylinders from the impression cyl- 75

printing unit comprising a common impression cylinder and pairs of design and transfer cylinders, their drive, and means for stopping the pairs of design and transfer cylinders without stopping the impression cylinder and for stopping the pairs of design and transfer cylinders independently of each other.

30. In a multi color offset printing press, a printing unit comprising a common impression cylinder and pairs of design and transfer cylinders, web advancing means, their drive, and means for stopping the pairs of design and transfer cylinders without stopping the impression cylinder and web advancing means and for stopping the pairs of design and transfer cylinders independently of each other.

31. In a multi color offset printing press, a printing unit comprising a common impression cylinder and pairs of design and transfer cylinders, their drive, means for driving the pairs of design and transfer cylinders independently of the impression cylinder and independently of each other, and means for driving the impression cylinder independently of its design and transfer cylinders.

32. In a multi color offset printing press, a printing unit comprising a common impression cylinder and pairs of design and transfer cylinders, web advancing means, their drive, means for driving the pairs of design and transfer cylinders independently of the impression cylinder and web advancing means and independently of each other, and means for driving the impression cylinder and web advancing means together, independently of the design and transfer cylinders.

33. In a multi color offset printing press, a printing unit comprising a common impression cyl-

inder and pairs of design and transfer cylinders, their drive, means for driving or stopping the pairs of design and transfer cylinders independently of the impression cylinder and independently of each other, and means for driving or stopping the impression cylinder independently of its design and transfer cylinders.

34. In a multi color offset printing press, a printing unit comprising a common impression cylinder and pairs of design and transfer cylinders, web advancing means, their drive, means for driving or stopping the pairs of design and transfer cylinders independently of the impression cylinder and web advancing means and independently of each other, and means for driving or stopping the impression cylinder and web advancing means together, independently of the design and transfer cylinders.

35. In a multi color offset printing press, a printing unit comprising a common impression cylinder and pairs of design and transfer cylinders, their drive, means for stopping the design and transfer cylinders without stopping the impression cylinder, and means for stopping the impression cylinder without stopping the design and transfer cylinders.

36. In a multi color offset printing press, a printing unit comprising a common impression cylinder and pairs of design and transfer cylinders, web advancing means, their drive, means for stopping the design and transfer cylinders without stopping the impression cylinder and web advancing means, and means for stopping the impression cylinder and web advancing means without stopping the design and transfer cylinders.

HOWARD M. BARBER.
